MAGAZINE OR CONTAINER FOR HOLDING
AND DISPENSING RAZOR BLADES

Frank Arthur Tuerff, South Orange, N. J., assignor to Vulcan Safety Razor Corporation, Maplewood, N. J., a corporation of New Jersey

Application January 28, 1948, Serial No. 4,803

12 Claims. (Cl. 30—40)

1

This invention relates to a magazine or container adapted to hold a plurality of safety razor blades, said magazine or container including means for successively dispensing the blades therefrom.

The invention has for an object to provide a novel construction of magazine or container adapted to hold a plurality of safety razor blades of the conventional double edged type; said magazine or container having means for successively discharging the blades therefrom as required for use.

The invention has for a further object to provide a razor blade magazine or container having novel means for holding a plurality of blades therein in superposed spaced apart and stacked relation; the magazine being provided with a discharge mouth parallel to the planes of the blades contained therein, said discharge mouth being constructed to receive and seat the head of a safety razor in aligned opposition to the stack of contained blades; and said blade holding means being manipulatable to discharge a blade from the stack thereof onto the head of a razor to which the magazine or container is applied, thus avoiding necessity for handling a blade with the fingers when assembling the same with the razor.

Another object of the invention is to provide, in a safety razor blade magazine or container as above characterized, means for retaining the blades in aligned stack or column forming relation against substantial shifting either longitudinally or laterally, and so that the sharpened edges of the blades are prevented from contacting the magazine or container walls, and thus guarded against injury.

Other objects of this invention, not at this time more particularly enumerated, will be understood from the following detailed description of the same.

Illustrative embodiments of the invention are shown in the accompanying drawings, in which:

Fig. 1 is a top end view; and Fig. 2 is a bottom end view of the razor blade dispensing magazine or container according to this invention.

Fig. 3 is a longitudinal vertical section through the magazine or container, taken on line 3—3 in Fig. 1, but drawn on an enlarged scale, and showing, by broken lines, a razor applied to the magazine or container ready for the reception of a blade to be discharged therefrom; Fig. 4 is a transverse vertical sectional view, taken on line 4—4 in Fig. 3; Fig. 5 is a view similar to that of Fig. 4, but showing a blade as applied to the razor by manipulation of the blade holding and dis-

2

pensing means of the magazine or container; Fig. 6 is a fragmentary transverse vertical section, taken on line 6—6 in Fig. 3; and Fig. 7 is a fragmentary horizontal section, taken on line 7—7 in Fig. 3.

Fig. 8 is a top end view of a modified form of the blade dispensing magazine or container of this invention; and Fig. 9 is a transverse vertical sectional view, in part elevation, taken on line 10—9 in Fig. 8.

Fig. 10 is a side elevational view, in part section, of the blade holding and dispensing magazine showing a removable cover for the bottom open end thereof ready for application thereto, the application of said cover to said bottom open end of the magazine or container being shown by broken lines.

Similar characters of reference are employed in the hereinabove described views, to indicate corresponding parts.

The novel razor blade dispensing magazine or container according to this invention comprises a downwardly open rectangular casing formed by a top wall 11, opposite side walls 12, and opposite end walls 13. This casing is made of selected depth suitable to accommodate a stack or column of safety razor blades of desired number.

The magazine or container is adapted to house safety razor blades 15 of the conventional double edged type. Blades of this type are provided with a suitably shaped longitudinal medial slot 16 intersected by a central circular hole or eye 17, and such blades are further provided with corner indentations or notches 18, whereby to provide the blade bodies with end portions 19 of reduced width.

Dependent from the top wall 11 of the casing, to extend downwardly in a central position within the upper interior of the casing, is an externally screw-threaded rotatable blade supporting

and dispensing shaft 20, the lower end of which terminates within the casing interior above the open bottom or mouth of the casing. Said blade supporting and dispensing shaft 20 possesses a mean diameter (i. e. a diameter between the bottoms of the screw-thread) which is slightly less than the diameter of the circular hole or eye 17 with which each blade 15 is provided, whereby the blades may be threaded onto said shaft so that the marginal portions of said holes or eyes 17 are embraced between convolutions of the screw-thread of the shaft, and thus adapted to cooperate with the latter in the manner of a female thread.

When a plurality of blades are thus threaded successively onto the supporting and

3
dispensing shaft 20, the blades will be spaced apart one from another along said shaft at distances corresponding to the pitch of the shaft screw-thread, and thereby superposed to form a stack or column of blades within the upper interior of the casing (see Figs. 3 and 4).

In one and a preferred construction, as shown in Figs. 1 to 7 inclusive, the upper end of the blade supporting and dispensing shaft 20 is provided with a thrust bearing plate 21, which is suitably affixed thereto so as to rotate therewith. This thrust bearing plate 21 bears against the under face of the top wall 11 of the casing so as to prevent upward axial movement or displacement of the shaft 20. The upper end of the blade supporting and dispensing shaft 20 terminates in an axially extending journal portion 22 which is journaled in a bearing opening 23 with which the top wall 11 of the casing is provided. Said journal stud portion 22 projects exteriorly from the top wall 11 of the casing, and fixed upon the projecting end of the journal portion 22 is a manipulatable finger-piece or knob 24, by means of which the blade supporting and dispensing shaft 20 can be rotated. The finger-piece or knob 24 bears against the outer surface of the casing top wall 11, thus holding the shaft 20 against downward axial movement or displacement from its operative assembled relation to the casing top wall, and therefore maintained in operative assembled disposition within the casing interior.

Means is provided for limiting the direction of rotation of the blade supporting and dispensing shaft 20 to one which will result in down-feeding movement therealong of the blades 15 supported thereby, and in successive discharge of the blades from the lower free end of said shaft. If the screw-thread of the blade supporting and dispensing shaft 20 is a right hand thread (as shown), this means is so arranged as to permit rotation of the shaft in counterclockwise direction, while preventing rotation thereof in the opposite or clockwise direction. An illustrative form of means for so controlling the operative rotative movement of the blade supporting and dispensing shaft 20, as shown more particularly in Figs. 3, 6 and 7, comprises a detent member 25, which is affixed to the upper end portion of the shaft 20 so as to rotate therewith, and so as to underlie the thrust bearing plate 21. Said detent member 25 is formed to provide a substantially radially extending spring arm 26 which terminates in an upstanding check-nosing 27. The thrust bearing plate 21 is provided with an opening 28 to permit upward extension of said check-nosing 27 therethrough and into a corresponding opening 29 provided in the casing top wall 11. The opening 29 is formed at one side to provide a perpendicular stop shoulder 30 which is adapted to be normally abutted by said check-nosing 27, so as to stop the blade supporting and dispensing shaft 20 against movement in clockwise direction. Said opening 29 is formed at its opposite side to provide a downwardly inclined cam portion 31, which is operative to depress the check-nosing 27 so as to withdraw the latter, against the tension of the spring arm 26 from the opening 29, when said check-nosing is moved in counterclockwise direction, thus permitting rotation of the blade supporting and dispensing shaft 20 in like counterclockwise direction.

The interior of the casing, although of a length substantially corresponding to the lengths of the blades 15, is of a width appreciably in excess of the widths of the blades, so that the blades

5 as supported within the casing, and as guided for downward movement therethrough by means presently to be described, will be so disposed relative to the casing side walls 12 that the sharpened cutting edges of the blades will be spaced away from said side walls and prevented from making injurious or dulling contact therewith.

10 Provided within the internal junctures of the side and end walls 12 and 13 of the casing are vertically disposed or perpendicular guide ribs 32, which are arranged to extend between the top wall 11 and the open bottom or mouth of the casing. These guide ribs are of cross-sectional shape to respectively correspond to and engage within the respective corner notches 18 of the blades 15, and laterally opposed guide ribs are spaced apart correspondingly to the widths of the end portions 19 of the blades; all whereby the blades, although free to move bodily downward through the interior of the casing, are nevertheless held against undue longitudinal and lateral shifting movements, and also against rotative movement about the axis of the screw-threaded shaft 20 by which the plurality of said blades are supported in a stack or column formation within the casing interior.

15 The stack or column of blades 15, as suspended by the blade supporting and dispensing shaft 20 within the casing, is so disposed that its lower end is spaced above the plane of the open bottom or mouth of the casing, thus providing within the open bottom end of said casing a space or socket 33 for the reception of the head H of a safety razor R, whereby the casing can be applied to the razor head so as to oppose the bottom-most blade of the stack or column of blades thereto, subject to discharge of said bottom-most blade, by operative manipulation of the blade supporting and dispensing shaft 20, for deposit upon and in assembled relation to the razor head. Within said space or socket 33, the guide ribs 32 are cut away or recessed to provide razor head seating shoulders or stops 34, the latter being upwardly offset from the plane of the open end or mouth of the casing.

20 Before applying the casing to the razor head H, the blade clamp-cap C of the razor is displaced from said head H, whereby the blade receiving top of the latter, together with the blade engaging projections P with which the head is provided, are exposed for reception of a blade 15. When the casing is applied to the razor head H, the ends of the latter will be abutted against the shoulders or stops 34, so that by engagement therewith and as straddled by reduced end portions 35 of the guide ribs 32, which extend below the shoulders or stops 34, the razor head will not only be disposed in a plane adjacently below and parallel to the face plane of the bottom-most blade 15 of the stack or column thereof, but also in longitudinally aligned relation to the latter so as to dispose the blade engaging projections P of the razor head H in aligned relation to the medial slot 16 of said blade.

25 After the casing has been operatively assembled with the razor head H, as above described, the bottom-most blade 15 of the contained stack or column of blades can be discharged and dropped over the blade engaging projections P and onto the razor head H by rotating the finger-piece or knob 24 in counterclockwise direction one full revolution. Such manipulation of the finger-piece or knob 24 rotates the thrust bearing plate 21 and detent member 25, so that the check-

nosing 27 of the latter rides out of the opening 29 of the casing top wall 11, and travels around beneath said top wall until it is again brought into registration with and so as to reenter said opening 29, thus indicating the completion of one full revolution of the finger-piece or knob.

The turning of the finger-piece or knob 24 one full revolution causes the blade supporting and dispensing shaft 20 to make a corresponding full revolution, whereby the blades 15 of the stack 10 or column thereof, as engaged by the screw-thread of the shaft, and as held against rotative movement by the casing, are all caused to descend along the shaft a distance corresponding to the pitch of the screw-thread thereof. Such down-feeding movement of the stack or column of blades causes the bottom-most blade to feed off from the lower free end of the shaft, and thus to be released from the support of the screw-thread. When the bottom-most blade is thus released, the same drops, by gravity, onto the razor head H and over the blade engaging projections P thereof (see Fig. 5).

After a blade is thus discharged from the casing onto the razor head H, the casing is removed from the latter, and thereupon the blade clamping cap C is applied in its operative blade engaging relation to the razor head. It will be obvious that these operations can all be performed without necessity for the operator to touch a blade at any time, and consequently all risk of cutting the fingers is positively eliminated. The above described blade dispensing operations may be repeated until the last blade of the stack or column thereof has been discharged and the casing is empty.

Referring to Figs. 8 and 9, there is shown thereby a modified arrangement for mounting and actuating the screw-threaded blade supporting and dispensing shaft 20 of the magazine. In this modified construction, the external finger-piece or knob 24 is eliminated, and the thrust bearing plate is modified so as to serve both as a journaling support for the shaft 20 as well as a means by which the latter can be actuated. To this end a circular bearing plate 36 of a diameter exceeding the width of the casing is provided. Said circular bearing plate 36 is rotatably supported in bearing openings 37 with which the side walls 12 of the casing are provided, and which are conformable to opposite peripheral portions of said bearing plate. The bearing openings 37 underlie the top wall 11 of the casing, so as to support said bearing plate 36 contiguous to the inner or under face of said casing top wall. The blade supporting and dispensing shaft 20 is suitably affixed by its upper end to said bearing plate 36, so as to depend from the latter, and so as to rotate therewith. Affixed to the blade supporting and dispensing shaft 20, so as to underlie the bearing plate 36, is the detent member 25 having the spring arm 26 which terminates in the check-nosing 27. Said check-nosing 27 projects upwardly through the bearing plate 36 for releasable engagement in the opening 29 of the casing top wall 11, all in the same manner and for the same purposes as already set forth in connection with the heretofore first described form of the blade holding and dispensing device. It will be obvious, that by engaging opposite exteriorly projecting peripheral portions of the bearing plate 36, rotative movement in proper direction may be imparted thereto, whereby to rotate the blade supporting and dispensing shaft 20

20 for the blade discharging operations above described.

As shown in Fig. 10, removable cover means 38 may be provided, if desired, for closing the open bottom end or mouth of the magazine casing.

It will be understood that variation in the detail construction and arrangement of the parts of the device, and in its blade holding capacity, may be made without departing from the scope of this invention as defined in the here following claims.

Having now described my invention, I claim:

1. A device for the purposes described comprising a downwardly open casing, a stack of centrally perforate razor blades within said casing, a rotatable screw-threaded blade supporting and dispensing shaft journaled in the top wall of the casing to extend downwardly within the casing toward the open bottom thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lowermost turn, means to prevent rotative displacement of the supported blades, and means connected with the shaft exteriorly of the top wall of the casing for rotatively manipulating said shaft in direction to feed the supported blades downwardly therewith along with accompanying release and discharge by gravity of a bottom-most blade through the open bottom of the casing.

2. A device for the purposes described comprising a downwardly open casing, a stack of centrally perforate razor blades within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lowermost turn, means to prevent rotative displacement of the supported blades, means connected with the shaft exteriorly of the top wall of the casing for rotatively manipulating said shaft in direction to feed the supported blades downwardly therewith along with accompanying release and discharge of a bottom-most blade, and means to position the head of a safety razor, when inserted within the open bottom of the casing, in aligned opposition to the supported blades, whereby to receive a bottom-most blade upon release and discharge thereof.

3. A device for the purposes described comprising a downwardly open casing having an internal cross-sectional shape substantially corresponding to the peripheral shape of corner-notched, centrally perforate and slotted, double edged safety razor blades, a stack of said blades housed within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lowermost turn, and means connected with the shaft exteriorly of

the top wall of the casing for rotatively manipulating said shaft in direction to feed the supported blades downwardly therealong with accompanying release and discharge by gravity of a bottom-most blade through the bottom opening of the casing.

4. A device for the purposes described comprising a downwardly open casing having an internal cross-sectional shape substantially corresponding to the peripheral shape of corner-notched, centrally perforate and slotted, double edged safety razor blades, a stack of said blades housed within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lower-most turn, means connected with the shaft exteriorly of the top wall of the casing for rotatively manipulating said shaft in direction to feed the supported blades downwardly therealong with accompanying release and discharge of a bottom-most blade, and means to position the head of a safety razor, when inserted within the open bottom of the casing, in aligned opposition to the superposed blades, whereby to receive a bottom-most blade upon release and discharge thereof.

5. A device for the purposes described comprising a downwardly open casing, a stack of centrally perforate razor blades within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lower-most turn, means to prevent rotative displacement of the supported blades, means connected with the shaft exteriorly of the top wall of the casing for rotatively manipulating the shaft so as to feed the supported blades downwardly therealong with accompanying release and discharge of a bottom-most blade, detent means rotatable with said shaft, and the top wall of said casing having means engageable by said detent means, whereby to indicate completion of single revolutions of said shaft in blade down-feeding direction.

6. A device for the purposes described comprising a downwardly open casing, a stack of centrally perforate razor blades within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-threaded support and space the blades in superposed relation with the bottom-most blade releasably supported by the lowermost turn, means to prevent rotative displacement of the supported blades, means connected with the shaft exteriorly of the top wall of the casing for rotatively manipulating the shaft so as to feed the supported blades downwardly therealong with accompanying release and discharge of a bottom-most blade, detent

means rotatable with said shaft, the top wall of said casing having means engageable by said detent means, whereby to indicate completion of single revolutions of said shaft in blade down-feeding direction, and means to position the head of a safety razor, when inserted within the open bottom of the casing, in aligned opposition to the superposed blades, whereby to receive a bottom-most blade upon release and discharge thereof.

7. A device for the purposes described comprising a downwardly open casing having an internal cross-sectional shape substantially corresponding to the peripheral shape of corner-notched, centrally perforate and slotted, double edged safety razor blades, a stack of blades housed within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lowermost turn, means connected with the shaft exteriorly of the top wall of the casing for rotatively manipulating said shaft so as to feed the supported blades downwardly therealong with accompanying release and discharge of a bottom-most blade, detent means rotatable with said shaft, and the top wall of said casing having means engageable by said detent means, whereby to indicate completion of single revolutions of said shaft in blade down-feeding direction.

8. A device for the purposes described comprising a downwardly open casing having an internal cross-sectional shape substantially corresponding to the peripheral shape of corner-notched, centrally perforate and slotted, double edged safety razor blades, a stack of blades housed within the casing, a rotatable screw-threaded blade supporting and dispensing shaft dependent within the casing from the top wall thereof, said shaft having a mean diameter slightly less than the width of the blade perforations whereby said shaft can be threaded through said blades so that successive turns of the shaft screw-thread support and space the blades in superposed relation with the bottom-most blade releasably supported by the lowermost turn, means connected with the shaft exteriorly of the top wall of the casing for rotatively manipulating said shaft so as to feed the supported blades downwardly therealong with accompanying release and discharge of a bottom-most blade, detent means rotatable with said shaft, and the top wall of said casing having means engageable by said detent means, whereby to indicate completion of single revolutions of said shaft in blade down-feeding direction.

9. A dispensing magazine for safety razor blades of the corner-notched, centrally perforate and slotted, double-edged type comprising a downwardly open casing, a stack of blades housed in the casing, a rotatable screw-threaded blade supporting and dispensing shaft dependent within the casing, said shaft having a journal portion axially extending from its upper end and journaled in and through the top wall of the casing,

a knob fixed on the exterior end of said journal portion for rotating said shaft, said shaft having a mean diameter slightly less than the width of the blade perforations whereby said shaft can be threaded through a plurality of said blades so that successive turns of the shaft screw-thread support and space the blades in superposed relation with the bottom-most blade releasably supported by the lowermost turn, perpendicular guide ribs at the internal corners of the casing to engage blade corner-notches, whereby to retain the blades against rotative displacement and to guide the same during downward movement thereof through the casing.

10. A dispensing magazine for safety razor blades of the corner-notched, centrally perforate and slotted, double-edged type comprising a downwardly open casing, a stack of blades housed in the casing, a rotatable screw-threaded blade supporting and dispensing shaft dependent within the casing, said shaft having a journal portion axially extending from its upper end and journaled in and through the top wall of the casing, a knob fixed on the exterior end of said journal portion for rotating said shaft, said shaft having a mean diameter slightly less than the width of the blade perforations whereby said shaft can be threaded through a plurality of said blades so that successive turns of the shaft screw-thread support and space the blades in superposed relation with the bottom-most blade releasably supported by the lowermost turn, perpendicular guide ribs at the internal corners of the casing to engage blade corner-notches, whereby to retain the blades against rotative displacement and to guide the same during downward movement thereof through the casing, and said guide ribs being recessed at their lower end portions to provide seating shoulders within the open bottom end of the casing, said seating shoulders being engageable by the head of a safety razor, when it is inserted within the open bottom end of the casing, whereby to position said head in aligned opposition to the superposed blades for reception of a bottom-most blade upon release and discharge thereof.

11. A dispensing magazine for safety razor blades of the corner-notched, centrally perforate and slotted, double-edged type comprising a downwardly open casing, a stack of blades housed in the casing, a rotatable screw-threaded blade supporting and dispensing shaft dependent within the casing, said shaft having a journal portion axially extending from its upper end and journaled in and through the top wall of the casing, a knob fixed on the exterior end of said journal portion for rotating said shaft, said shaft having a mean diameter slightly less than the width of the blade perforations whereby said shaft can be threaded through a plurality of said blades so

that successive turns of the shaft screw-thread support and space the blades in superposed relation with the bottom-most blade releasably supported by the lowermost turn, perpendicular guide ribs at the internal corners of the casing to engage blade corner-notches, whereby to retain the blades against rotative displacement and to guide the same during downward movement thereof through the casing, detent means rotatable with said shaft, and the top wall of said casing having means engageable by said detent means, whereby to indicate completion of single revolutions of said shaft in blade down-feeding direction.

15. 12. A dispensing magazine for safety razor blades of the corner-notched, centrally perforate and slotted, double-edged type comprising a downwardly open casing, a stack of blades housed in the casing, a rotatable screw-thread blade supporting and dispensing shaft dependent within the casing, said shaft having a journal portion axially extending from its upper end and journaled in and through the top wall of the casing, a knob fixed on the exterior end of said journal portion for rotating said shaft, said shaft having a mean diameter slightly less than the width of the blade perforations whereby said shaft can be threaded through a plurality of said blades so that successive turns of the shaft screw-thread support and space the blades in superposed relation with the bottom-most blade releasably supported by the lowermost turn, perpendicular guide ribs at the internal corners of the casing to engage blade corner-notches, whereby to retain the blades against rotative displacement and to guide the same during downward movement thereof through the casing, detent means rotatable with said shaft, the top wall of said casing having means engageable by said detent means, whereby to indicate completion of single revolutions of said shaft in blade down-feeding direction, and said guide ribs being recessed at their lower end portions to provide seating shoulders within the open bottom end of the casing, said seating shoulders being engageable by the head of a safety razor, when it is inserted within the open bottom end of the casing, whereby to position said head in aligned opposition to the superposed blades for reception of a bottom-most blade upon release and discharge thereof.
